UNITED STATES PATENT OFFICE.

MYRON B. HAMMOND, OF BRIDGEPORT, CONNECTICUT.

HOSE-SUPPORTER.

SPECIFICATION forming part of Letters Patent No. 769,218, dated September 6, 1904.

Original application filed March 26, 1902, Serial No. 100,068. Divided and this application filed June 16, 1904. Serial No. 212,789. (No model.)

To all whom it may concern:

Be it known that I, MYRON B. HAMMOND, a citizen of the United States, residing at Bridgeport, in the county of Fairfield and State of Connecticut, have invented certain new and useful Improvements in Hose-Supporters; and I do hereby declare the following to be a full, clear, and exact description of the invention, such as will enable others skilled in the art to which it appertains to make and use the same.

My invention relates to that class of hose-supporters which comprises a flexible pad from the bottom of which depend the stocking-engaging members, while secured to the upper portion of said pad is a metallic fastening device adapted to engage with the corset-clasp element, so that the supporters will be suspended from the corset at or about the point where the sections of the corset meet in front. Heretofore many hose-supporters of this sort have been made which comprised a single flexible pad element and a single metallic fastener element secured to the upper central portion of the pad, so that the pad is suspended from or upon either the stud element or the loop element of the clasp.

My invention contemplates two separate pad elements, and from the upper portion of each element extends a metallic fastener device, one of said devices adapted to engage and be suspended from the loop element of the clasp, while the other of said devices is adapted to be engaged with and suspended from the stud element of the clasp, the object of my invention being to provide a hose-supporter which shall be suspended from two points of the corset at or about the place where the sections of the corset meet in front.

In the accompanying drawings, which form a part of this application, Figure 1 is a front elevation showing a section of a corset with my improvement applied thereto. Fig. 2 is a rear perspective view of the metallic fastener which attaches over the loop element of the corset-clasp, and Fig. 3 is a rear perspective view of the metallic fastener which attaches over the stud element of the corset-clasp.

Similar numbers of reference denote like parts in the several figures of the drawings.

1 2 are the corset-sections, which carry, respectively, the loop 3 and stud 4 of the usual form of corset-clasp.

5 6 are flexible pads, which when their inner edges are abutted together present the 55 appearance and advantages of the usual form of pad.

7 is a metallic fastener secured in any suitable manner to the upper portion of the pad 5 and provided with rearwardly-extending 60 flanges 8 9, separated by a distance about equal to the width of the loop 3, said fastener being cut away, as shown at 10, whereby a clear space is left between said flanges. These flanges are resilient, so that when the fastener 65 is applied they will tightly bear against the corset-busk, which carries the loop, while the loop itself will be embraced between the flanges, thus preventing vertical displacement of the fastener. This form of fastener is 70 shown, described, and claimed in my Letters Patent No. 679,893, issued August 6, 1901, and I therefore do not wish to be understood as claiming any novelty in the fastener itself, and I have illustrated this particular construction as a preferred form of fastener, and I do not wish to be limited thereby, since any other form of fastener adapted to engage with the loop or its eye will answer the purposes 75 of my invention.

80 11 is a metallic fastener secured to the upper portion of the pad 6 and provided with rearwardly-extending resilient flanges 12 13 and also having its edges cut away, as shown at 14, a recess 15 being provided in the upper part of said cut-away portion to accommodate the stud of the corset-clasp. When applied to the edge of the corset-busk carrying the stud, the flanges 12 13 will bear tightly 85 against the under side of the busk, while the shank of the stud will lie within the recess 15. The fastener 11 is thin enough so that it will not interfere with the ready manipulation of the elements of the corset-clasp. This fastener 11 is very readily applied and removed.

90 In applying the same the upper flange 12 is first placed behind the busk and the fastener drawn downwardly and over the top of the stud until it passes over the head of the stud and lies snugly behind the same at the extreme 95 100

backward part of the cut-away portion. This leaves the fastener in a slanting position with the lower flange immediately beyond the edge of the busk, and this flange is then readily 5 pushed into position and the fastener drawn down, so as to bring the stud of the corset-clasp within the recess 15. In removing the fastener the latter is first pushed upwardly, so as to bring the stud opposite to the extreme 10 rear part of the cut-away portion 14, and the lower part of the fastener is then swung outwardly, so as to bring the lower flange clear of the busk. The lower portion of the fastener is then slightly lifted and swung inwardly 15 over the top of the busk and the fastener then forced upwardly and to one side, thus bringing the upper flange clear of the busk. I do not wish to be understood as claiming herein any specific construction of this fastener 11, 20 since an approved form of fastener of this description is made the subject of an application for Letters Patent filed by me April 17, 1902, under Serial No. 103,372, and, moreover, any 25 sort of a fastener which will engage the busk and the stud is ~~not~~ suitable for the purposes of my invention, the gist of which rests in the broad idea of two separate flexible pad elements provided with separate metallic fasteners at the top adapted to engage with and be 30 suspended by the loop and stud, respectively, of a corset-clasp, so that these pads with their fasteners will become permanently locked on the corset and are not disturbed by the clasping and unclasping of the same. It will thus 35 be seen that when the parts of my improved hose-supporter are in position on the corset all the advantages of an integral pad will be preserved, while the sections of the corset may be clasped and unclasped and the corset 40 removed entirely without disturbing the parts of my improvement.

In the present application I do not wish to

be understood as claiming, broadly, "a hose-supporting device composed of two parts each having a flange adapted to embrace one of the 45 corset-steels, one of said parts being adapted to engage the eye of the corset-clasp and the other of said parts being adapted to engage the stud of the corset-clasp," since such construction is claimed in an application for Letters 50 Patent of the United States for improvement in hose-supporters, filed by me March 26, 1902, Serial No. 100,068.

What I do claim in the present application, and desire to secure by Letters Patent, is— 55

1. A hose-supporter comprising separate pads, said pads having secured to their upper portions metallic fasteners adapted to engage respectively with the loop and stud elements of a corset-clasp and independently of each 60 other at all times, whereby the device as a whole is suspended from the corset at two independent points of support where the sections of the corset meet, substantially as set forth. 65

2. A hose-supporter comprising two separate pads which have metallic fasteners secured to their upper ends, each metallic fastener having rearwardly-extending resilient flanges adapted to respectively engage the 70 corset-busks, the flanges of one fastener adapted to be disposed on opposite sides of the loop of the corset-clasp, while the flanges of the other fastener are adapted to be disposed on opposite sides of the stud of the corset-clasp, 75 the latter fastener being also constructed to engage with and be suspended by said stud, substantially as set forth.

In testimony whereof I affix my signature in presence of two witnesses.

MYRON B. HAMMOND.
